US00D879319S

(12) **United States Design Patent** (10) **Patent No.:** **US D879,319 S**
(45) **Date of Patent:** **** Mar. 24, 2020**

(54) **SAMPLE STORAGE**

(71) Applicant: **KOBE BIO ROBOTIX CO., LTD.**,
Katou-shi, Hyogo (JP)

(72) Inventors: **Shinichiro Kakuda**, Kobe (JP); **Yoko Nakahana**, Nishinomiya (JP)

(73) Assignee: **KOBE BIO ROBOTIX CO., LTD.**,
Hyogo (JP)

(**) Term: **15 Years**

(21) Appl. No.: **29/703,818**

(22) Filed: **Aug. 29, 2019**

(57) **CLAIM**

The ornamental design for a sample storage, as shown and described.

DESCRIPTION

FIG. 1 is a perspective view of a sample storage showing our new design;

FIG. 2 is a front elevation view thereof of the sample storage depicted in FIG. 1;

FIG. 3 is a rear elevation view thereof;

FIG. 4 is a left side elevation view thereof of the sample storage depicted in FIG. 1;

FIG. 5 is a right side elevation view thereof;

FIG. 6 is a top plan view thereof;

FIG. 7 is a bottom plan view thereof;

FIG. 8 is a perspective view of a second embodiment of a sample storage showing our new design;

FIG. 9 is a front elevation view thereof;

FIG. 10 is a rear elevation view thereof;

FIG. 11 is a left side elevation view thereof;

FIG. 12 is a right side elevation view thereof of the sample storage depicted in FIG. 8;

FIG. 13 is a top plan view thereof; and,

FIG. 14 is a bottom plan view thereof.
